UNITED STATES PATENT OFFICE.

CHARLES H. ALLEN AND GLENN S. SOSEMAN, OF CHICAGO, ILLINOIS, ASSIGNEES, BY
MESNE ASSIGNMENTS, TO THE ALLENLITE COMPANY, A CORPORATION OF ILLINOIS.

HEADLIGHT.

Application filed June 16, 1922, Serial No. 568,774. Renewed November 15, 1924.

To all whom it may concern:

Be it known that we, CHARLES H. ALLEN and GLENN S. SOSEMAN, citizens of the United States, and residents of the city of

5 Chicago, in the county of Cook and State of Illinois, have invented certain new and useful Improvements in a Headlight; and we do hereby declare that the following is a full, clear, and exact description of the same, 10 reference being had to the accompanying drawings, and to the numerals of reference marked thereon, which form a part of this specification.

This invention relates to a headlight, and 15 particularly to a headlight which is provided with a compound reflector adapted to project light forwardly and outwardly and at the same time to avoid objectionable upward reflection.

20 It is an object of the present invention to provide a headlight having a compound reflector, the component portions of which are offset.

It is another object of this invention to 25 provide a headlight of the class described wherein the reflecting member is adjustable.

It is a further object of the invention to 30 provide a headlight having means for permitting the emission of light in a transverse direction.

It is also an object of this invention to provide a headlight having a compound reflector and having a light source, the axis of which is parallel to the longitudinal axis 35 of the casing.

It is an important object of this invention to provide a headlight having a compound reflector, a portion of which is adapted to reflect light downwardly and another portion of which is adapted to reflect light substantially horizontally, the light reflected from said reflectors being resolved to properly illuminate a surface over which the headlight is being moved.

45 It is finally an important object of this invention to provide a headlight of the class described which may be economically manufactured and easily adjusted.

Other and further important objects of 50 this invention will be apparent from the disclosures in the specification and the accompanying drawings.

The invention (in a preferred form) is 55 shown on the drawings and hereinafter more fully described.

On the drawings:

Figure 1 is a central vertical section through a headlight embodying the principles of this invention.

Figure 2 is a front elevation of the head- 60 light shown in Figure 1.

Figure 3 is a section on the line 3—3 of Figure 1.

Figure 4 is a front elevation of the sup- 65 port for the light source.

Figure 5 is a slightly enlarged section on the line 5—5 of Figure 4.

Figure 6 is a front elevation of a slightly modified form of headlight embodying the 70 principles of this invention.

Figure 7 is an enlarged section on the line 7—7 of Figure 6.

Figure 8 is a section on the line 8—8 of Figure 7.

Figure 9 is a slightly reduced section on the line 9—9 of Figure 7.

Figure 10 is a top plan view of one of the reflector members.

As shown on the drawings:

In the embodiment of this invention illustrated in Figures 1 to 5 inclusive, the headlight supporting structure comprises a cylindrical member or casing 1 which has a substantially spherically formed portion 2 fixedly or removably attached to one end

80 thereof in any suitable manner. The end of said cylindrical casing 1 opposite the spherically formed portion 2 is closed by a lens 3 which is formed of any suitable transparent material and which is retained between

85 the outer end of the casing 1 and a flanged retaining ring 4 which is removably secured over the outer end of the casing and which has a suitable gasket 5 interposed between

90 its inner face and the outer face of the transparent member 3. In order that said transparent member 3 may be resiliently retained in position adjacent the gasket 5 in the inner face of the flanged ring 4, a spring wire 6 is engaged inside the casing, said spring wire

95 100 having portions abutting the inner face of the transparent member 3 and other portions engaged under ears 7 which are struck inwardly from the cylindrical member 1. Suitable lugs 8 are secured to each side of

105 the cylindrical member or casing 1 and are adapted for engagement with the usual supporting forks which are provided for mounting headlights on motor vehicles and the like. A support for a light source is afford-

ed by transverse members 9 and 10 which are secured in the casing a short distance in rear of the transparent member 3 by spot-welding or otherwise securing angular portions 11 formed on said members to the inner wall of the cylindrical member 1. The inner faces of said members 9 and 10 abut each other, as shown in Figures 4 and 5, and if desired said members may be secured together intermediate their ends by riveting or in any other suitable manner. Oppositely formed longitudinal grooves 9' and 10' in said members 9 and 10 afford a passage whereby an electrical conductor may be led into the light source which ordinarily comprises an incandescent light bulb 12 which is mounted in a socket 13 which in turn is supported between outwardly formed portions 14 and 15 at the center of the members 9 and 10. The inner surface of the cylindrical member 1 is not coated with any special reflecting material and formed in the side walls of said member at points substantially equidistant from the transparent member 3 with the light source 12 are apertures which are closed by lenses 16 and 17 respectively, the aperture which is closed by the lens 16 being specially designed to allow of emission of light from the casing to illuminate a front license plate in cases where the headlight is used on a motor vehicle, and the aperture which is closed by the lens 17 being designed to permit the emanation of light to illuminate the front portion of the vehicle and the immediate surface supporting the same. Such auxiliary light emanating means add greatly to the usefulness of the headlight, especially when the same is used in connection with motor vehicles, and the practical use of these auxiliary apertures is made possible by the fact that the reflecting members do not extend into the forward portion of the headlight casing. It is of course understood that such apertures would not be needed for all conditions in which the headlight might be used and in such cases could be omitted.

The compound reflector unit which will now be described is mounted in the rear of the headlight casing substantially in the spherically formed portion 2, the reflector members being supported in the reflector support 18 which is provided at its forward end with an annular integral flange 19, the forward edge of said flange being engaged in a groove formed in the rear edge of a block or supporting member 20 secured to the upper portion of the cylindrical member 1 by riveting or other suitable means. The reflector support 18 is thus suspended inside the headlight casing from the block 20, and the lower portion thereof is frictionally held in position in the casing by means of a flat spring 21 which is engaged through an aperture in the flange 19 and

the outer end of which slidably and resiliently contacts the inner wall of the cylindrical member 1 at the lower portion thereof. Extending through the spherically formed portion 2 directly beneath the center thereof, is a short tubular member 22 which extends into the interior of said member a sufficient distance to afford a guide for a helical spring 23 which is engaged therearound between the inner side of the spherically formed portion 2 and the rear face of the reflector support 18, directly beneath a shelf or offset portion 24 which is formed in said reflector support 18. Said tubular member 22 affords an opening through which electrical conductors may be introduced into the headlight casing; and the helical spring 23 which is engaged therearound between the spherically formed portion 2 and the reflector support 18 acts to force the lower portion of said reflector support 18 outwardly. This tendency to outward movement of the reflector support 18 is resisted and prevented by means of an adjusting set screw 25 which is engaged through a threaded aperture in a bracket 26 secured to the bottom of the cylindrical member 1 on the inside of the casing and the end of which contacts an upwardly formed lug 27 on the flange 19. From this construction it is of course apparent that when said adjusting set screw 25 is rotated in one position, the reflector support 18 with the reflectors therein will have its lower portion moved forwardly in the headlight casing and when said adjusting set screw is rotated in the opposite direction said lower portion of the reflector support 18 will of course be moved toward the rear of the casing against the action of the helical spring 23. The reflectors comprising the compound reflector unit are spherical segments which are secured by cementing or otherwise to the front or concave face of the reflector support 18 above and below the shelf or offset portion 24. In the preferred form of this invention, double curvature glass reflectors 28 and 29 of the well-known Mangin, type are employed, but it is of course understood that these reflectors might be of the ordinary single curvature type without departing from the spirit of the present invention. As will be noted from an examination of Figure 1, the axis of the light source is slightly below the axis of the headlight casing and is substantially on the axis of the lower reflector segment 29 to cause a reflected horizontal beam of light. The axis of the upper reflector 28 also passes through the light source but forms a downwardly directed beam of light due to the offset angular position of the reflector. The light source is located at the foci of the reflectors. The light reflected from the two reflectors is

composed into a beam which because of the component from the reflector 29 extends forwardly for a great distance and because of the component from the reflector 28 is of 5 extreme intensity for a considerable distance in front of the headlight. Such an arrangement makes the headlight particularly valuable for use on motor vehicles since the surface traveled over is illuminated 10 brilliantly for a long distance ahead, while there are no upwardly directed rays to create an objectionable glare which might confuse the occupants of vehicles or other people traveling toward the headlight. In 15 the use of the double curvature reflectors of the type illustrated herein, refractive effects as well as reflection must be given consideration and this is provided for by the positioning of the reflectors in the reflector support 20 port 18 by positioning of the light source and finally by the adjustment of the member 18 by the adjusting set screw 25.

Figures 6 to 9 illustrate a headlight constructed according to the principles of this 25 invention wherein a modified form of casing or supporting member is employed and wherein the reflector units are permanently and rigidly positioned in the casing. The 30 casing of the type illustrated in Figures 6 to 9 inclusive is constructed of a composition material such as vulcanite, commercial redmanol or a similar substance, and comprises a forward cylindrical portion 30 and an integral formed rear portion 31 having 35 an offset shelf portion 32 corresponding to the shelf portion 24 shown in Figure 1 between the reflectors. The reflectors 33 and 34, similar to the reflectors 28 and 29, are secured in position in the rear of the headlight 40 casing by cementing the same to the concave faces of the member 31. Lugs or brackets 35 secured to the sides cast integral with the sides of the casing 30 afford means whereby the same may be supported 45 on suitable headlight brackets. Lens-closed apertures 36 and 37 are formed in the casing 30 in positions corresponding to the positions of the apertures which are closed by lenses 16 and 17 in the form of this invention 50 previously described. A light source 38 is supported in the casing by means of a transverse member 39 similar to the transverse light supporting structure hereinbefore described, and said light source is properly positioned relative to the reflectors 33 and 34 to attain a horizontal reflection from the lower reflector 34 and a downward and outward reflection from the upper reflector 33. Engaging the outer end of the cylindrical member 30 is a transparent member 40 which abuts a suitable gasket on the outer end of said cylindrical member and which is secured in position by a flanged ring 41 which in turn is secured to the casing 55 30 by means of a screw 42. By thus

constructing the headlight casing of redmanol, bakelite or vulcanite it is possible to obtain a light, durable and beautifully finished headlight which is highly desirable for certain uses. The headlight provided 70 by this invention is especially adapted for use on motor vehicles and as above indicated the component beam or shaft of light which is composed of the downwardly and outwardly directed rays from the reflectors 75 28 or 33, and the horizontal beam which is composed of the horizontally reflected rays from the reflector 29 or the reflector 34 combine to afford a compound beam or shaft of light which efficiently illuminates 80 the surface traveled over for a long distance ahead of the vehicle and which at the same time does not produce an objectionable glare. The adjustment for the reflector unit provided in the form of this invention 85 disclosed in Figures 1 to 5 inclusive affords means whereby the light may be properly adjusted to attain a maximum efficiency and to provide for varying conditions in headlight mounting, in shapes and positionings 90 of the light source.

The headlight of this invention may be economically manufactured, may be conveniently mounted on existing types of motor vehicles and other standard headlight supports, and being outwardly of substantially conventional appearance does not detract but rather adds to the appearance of the vehicle or other object on which it is mounted. 100

We claim as our invention:

1. A headlight comprising a casing, two reflectors adjustably mounted in the casing, said reflectors being positioned on opposite sides of a horizontal longitudinal plane 105 taken through the casing, one of said reflectors being offset rearwardly relative to the other reflector, a support extending transversely of the casing in front of said reflector members and below the axis of the casing, and a light source mounted on said support. 110

2. A headlight comprising a casing, a reflector supporting member associated therewith, said supporting member having two longitudinally offset reflector receiving portions, a reflector member in each of said portions, one member positioned to project light rays horizontally and the other member positioned to project light rays downwardly, means for adjusting the position of said reflector supporting member relative to the casing, and a light source in the casing in front of said reflector members. 115 120

3. A headlight comprising a casing, a reflector supporting member associated therewith, said supporting member having two longitudinally offset reflector receiving portions, a reflector member in each of said portions, one member positioned to project 125 130

light rays horizontally and the other member positioned to project light rays downwardly, resilient means for positioning said reflector supporting members, and a light source in the casing in front of said reflector members.

In testimony whereof, we have hereunto

subscribed our names in the presence of two subscribing witnesses.
